TOOL FOR APPLYING ELECTRICAL AND
TELEPHONE TIP TERMINALS

Leon Rosenthal, Baltimore, Md., assignor to Guild Manufacturing Company, Baltimore, Md., a partnership composed of Irving Katz and Albert D. Goldman, both of Baltimore, Md.

Application December 15, 1942, Serial No. 469,109

8 Claims. (Cl. 81—15)

My invention relates broadly to tools and more particularly to a tool for applying sleeve-like terminals to electrical conductors.

One of the objects of my invention is to provide a construction of tool for rapidly applying sleeve-like terminals to the ends of insulated conductors in order to permit electrical connection to be readily established with such conductors.

Another object of my invention is to provide a construction of tool comprising a multiplicity of simultaneously operating radially arranged knives between which an electrical conductor carrying a sleeve-like terminal may be introduced for displacing portions of the sleeve-like terminal to positions establishing electrical connection between the terminal and the electrical conductor with which the terminal is established.

Still another object of my invention is to provide a construction of tool for applying sleeve-like terminals over the insulation of insulated electrical conductors in which a multiplicity of knives are arranged in radial positions between which an electrical conductor having a sleeve-like cap or terminal slipped over the end thereof may be introduced with yieldable means for moving the knives inwardly to positions piercing the material of the sleeve-like member for displacing the material thereof to a position establishing electrical connection with the conductor, the knives being thereafter retractile for releasing the electrical conductor with the terminal applied thereto.

A further object of my invention is to provide a tool which operates to both establish electrical connection between a sleeve-like terminal and the conductive strands of an insulated wire and also curl or roll inwardly the circular end of the sleeve to provide a tight mechanical connection between the sleeve and the insulated wire.

A still further object of my invention is to provide a tool for applying sleeve-like terminals to insulated electrical conductors where the tool includes means for both lancing and curling the sleeve with respect to the insulated electrical conductor for establishing both a firm mechanical connection between the sleeve and the insulation of the conductor and an electrical connection between the sleeve and the electrical conductor through the insulation thereof.

Other and further objects of my invention reside in a construction of electrical terminal applying tool as set forth more fully in the specification hereinafter following by reference to the accompanying drawings, in which:

Figure 1 is a front elevation of the tool embody-

ing my invention; Fig. 2 is an end view of the tool shown in Fig. 1; Fig. 3 is an enlarged fragmentary vertical sectional view showing parts of the tool in section and parts of the tool in elevation, the tool being shown in a position prepared to receive the terminal capped end of insulated wire for application of the terminal to the end of the insulated wire; Fig. 4 is a view similar to the view illustrated in Fig. 3 showing the terminal capped end of an insulated wire introduced into the socket between the radially disposed knives; Fig. 5 is a view of the tool similar to the views shown in Figs. 3 and 4 but illustrating the parts shifted to operative position for lancing the material of the sleeve-like terminal for establishing electrical connection between the sleeve-like terminal and the electrical conductor and curling the edge of the sleeve-like terminal inwardly for providing a firm mechanical connection between the sleeve-like terminal and the insulation of the electrical conductor; Fig. 6 is a transverse sectional view taken on line 6—6 of Fig. 3; Fig. 7 is a transverse sectional view taken on line 7—7 of Fig. 3; Fig. 8 is a transverse sectional view taken on line 8—8 of Fig. 3, all of the parts in said Figs. 6, 7 and 8 being illustrated in position preparatory for performing a terminal applying operation; Fig. 9 is a transverse sectional view taken on line 9—9 of Fig. 5 illustrating the knives displaced to a position in which the terminal applying operation is performed; Fig. 10 is a side elevational view of the collet chuck through which the terminal capped end of the wire is introduced; Fig. 11 is a vertical sectional view through the collet chuck of Fig. 10 taken on line 11—11 of Fig. 12; Fig. 12 is a transverse sectional view through the collet chuck of Fig. 10 on line 12—12 thereof; Fig. 13 is a transverse sectional view taken on line 13—13 of Fig. 3 and illustrating the connection of the actuating means with the operating mechanism of the tool; Fig. 14 is a perspective view of one of the knives employed in the tool for lancing the material of the sleeve-like terminal into position for establishing electrical connection with the electrical conductor through the insulation of the conductor; Fig. 15 is a fragmentary portion of the end of an insulated conductor showing a sleeve-like terminal applied thereto in accordance with my invention; Fig. 16 is an enlarged fragmentary view of the knives in position preparatory for a lancing operation and showing the sleeve-like terminal centered within the spring collet chuck preparatory for a curling operation; and Fig. 17 is a view similar to the view shown in Fig. 16 but illustrating

the relative position of the parts when both the lancing and curling operations have been completed.

I have illustrated my invention as embodied in a hand tool for applying sleeve-like members to the ends of electrical conductors. The fact however that the mechanism of my invention is applied to a hand tool does not preclude the use of the same mechanism in a machine which may be hand or foot operated or motor operated for applying the sleeve-like terminals to the ends of electrical conductors. Accordingly, throughout the specification I desire that it be understood that the hand tool shown is illustrative of one of the uses of my invention and that the actuation of the parts of the device may be performed by any manual or automatically operated machine.

Referring to the drawings in detail, reference character 1 designates a shell member having 20 outstruck hollow side portions 1a and 1b. The upper end of the shell 1 is apertured at 1c as shown. A sleeve 2 is telescopically disposed within the shell 1 and is adapted to be reciprocated therein for controlling the mechanism of the tool. The sleeve 2 has an end lug 2a projecting therefrom apertured at 2b to allow the entry of securing member 2c. The securing member 2c may be a screw threaded bolt having a fastening nut thereon or a rivet or other transverse member. The transverse member 2c passes through the coacting interleaved portions of the actuating members 12a and 12b. Portions of actuating member 12a shown at 12c and 12d overlap as shown and are interconnected by the transversely extending member 2c. The actuating members 12a and 12b are each provided with pins 8a and 8b displaced from the transverse member 2c and which form pivotal connections for links 5a and 5b which are pivotally connected by means of pins 9a and 9b with the outstruck hollow side portions 1a and 1b. The action of this linkage is such that as actuating members 12a and 12b are brought together from the normal position illustrated in Fig. 3 to the position illustrated in Fig. 5, the transversely extending member 2c exerts pressure through lug 2a to shift the sleeve 2 to a position wholly within shell 1 as illustrated in Fig. 5.

The interior of the sleeve 2 has internal bores of different diameters as represented at 2d and 2e. In the portion of the sleeve 2d the expansive coil spring 7 is housed while in the portion 2e of the sleeve the coil spring 6 and the balance of the mechanism is housed. The change in internal diameter of the bore of sleeve 2 takes place along a transverse section illustrated at 2f. Just above the shoulder thus formed the plunger 3 is normally yieldingly supported on coil spring 7. The plunger 3 is a precision machined element having an end flange 3a thereon which is seated upon the end of coil spring 7. The coil spring 6 is concentrically disposed about the cylindrical body portion of the plunger 3 and is seated against the head 3a at one end and against the end of the cylindrical collet chuck member 11. That is to say, coil spring 6 forms a continuously expansive means disposed between the head formed by flange 3a on plunger 3 and the end of the cylindrical collet chuck member 11.

The cylindrical collet chuck member 11 is shown more clearly in Figs. 10, 11 and 12 and includes an inner bore of varying internal diameters, that is, a cylindrical portion of uniform section illus-

trated at 11a, a cylindrical portion of smaller section shown at 11b, a further cylindrical portion of still smaller section shown at 11c and frusto-conical end sections illustrated at 11d and 11e. The section 11c of the chuck provides an internal shoulder against which the raw peripheral edge of the sleeve-like terminal 15 abuts as the plunger 3 forces the terminal against the shoulder of the section 11c from the position 10 illustrated in Fig. 16 to the position illustrated in Fig. 17. The shoulder of section 11c is represented at 11f and is so curved that as the raw edge of sleeve 15 is forced against the shoulder, the material of sleeve 15 is forced to curl inwardly to form a substantially moisture-tight connection with the insulation material 17 of the electrical conductor 16 as shown in Fig. 17. The piercing operation which is commenced by entry of the points of the knives into the sleeve-like terminal 15 as will be hereinafter described is completed as a composite shearing and lancing operation as represented in Fig. 17 for completing electrical connection between the material of sleeve 15 and the wire 16.

The upper end of the collet chuck member is provided with an annular shoulder 11g having an angularly inclined cylindrical surface 11h thereon. The projecting end of the collet chuck member is represented at 11i. The collet chuck member is slotted throughout substantially the entire length thereof in the positions illustrated at 11j whereby the portions of the collet chuck member are rendered resilient and are adapted to be moved toward each other to a collapsed position or to spring outwardly away from each other to normal position. The slots 11j thus formed are of sufficient width to permit the angular movement of the knives shown at 4a, 4b and 4c therethrough.

The construction of the knives is shown more clearly in Fig. 14, from which it will be seen that one end of each knife is rounded as represented at 4a' and tapered toward the opposite end as represented at 4a''. A cam shaped lug 4a''' extends from the tapered portion 4a'' of the knife. The portion 4a'' of the knife has a recess 4a^{IV} formed therein of sufficient length to span the annular head 3b of the plunger 3 as shown in Figs. 3, 4 and 5. The cam shaped lug 4a''' is proportioned to fit wholly within the annular recess 3c of plunger 3 when the knives are moved inwardly to pierce the material of the sleeve-like terminal represented at 15 in Fig. 15. The knives are each provided with a straight face 4v from which extends the piercing or lancing knife blade 4v^I. The piercing or lancing knife blade 4v^I is of isosceles formation having a triangular shaped face 4v^{II} terminating in the point of the piercing knife blade 4v^I. This triangular shaped face lances or shears the material of the sleeve-like terminal 15 as the point of the piercing or lancing blade 4v^I shears the material of the sleeve-like terminal 15 as illustrated in Figs. 5 and 17, thereby establishing an electrical connection between the electrical conductor 16 and the sleeve-like terminal 15 through the insulation material 17.

The material of the metallic sleeve-like terminal 15 is pierced, sheared and bent inwardly from the cylindrical portion of the sleeve-like terminal 15 as represented at 18 in Figs. 5, 15 and 17. This operation is effected by the composite movement of plunger 3 axially within the spring collet chuck 11 and the radial inward movement

of the knives under control of the actuating means 12a and 12b. That is to say, the action of the actuating means 12a and 12b tends to force plunger 3 through the spring collet chuck from the position illustrated in Fig. 16 to the position shown in Fig. 17. As the knives pierce the material of the sleeve-like terminal 15 there is a movement of plunger 3 toward the shoulder 11j of the collet chuck such that the curling operation to force the material of the sleeve-like terminal 15 inwardly to form a mechanical connection with the insulation material 17 is effected and also the sleeve is moved against the knives to effect a lancing or shearing operation which forms the conducting tongues 18. The conducting tongues thus formed establish an electrical circuit between the electrical conductor and the sleeve-like terminal 15.

Each of the knives include a cam-like end portion 4^{VIII} which in normal position illustrated in Figs. 3 and 4 project; under the action of springs 6 and 7, to positions against the inside of the hood formed by the shell 1. The springs 6 and 7 tending to continuously force the knives to an open position, press the knives to the positions illustrated in Fig. 3 where the rear face of each knife represented at 4^{IX} is forced against the inside of the bore 2e of the sleeve 2. In this position the cam-like ends 4^{VIII} project beyond the peripheral edge of the sleeve 2 with the knives 4^{VI} retracted between slots 11i. In this retracted position the end of the insulated conductor with the terminal sleeve 15 slipped thereon may be introduced between the knives preparatory to the terminal applying operation. In the form of the terminal illustrated in Fig. 15, a tip 19 extends from the sleeve 15. The plunger 3 is provided with a complementary shaped bore 20 for receiving the tip 19 and allowing the sleeve-like portion of the terminal to be located in registry position with the several knives 4^{VI}. As the device is moved to the position illustrated in Fig. 4, the knives commence to engage the sleeve-like terminal 15. As this operation is continued the knives pierce the sleeve-like terminal 15 as heretofore explained. The operation thereafter is a composite shearing and lancing movement brought about by the axial movement of plunger 3 and the radial movement of the knives. The material of the sleeve-like terminal is actually moved against the knives as the knives move inwardly so that the lancing or shearing operation is performed quickly. The small triangular shaped portions of the material of the sleeve-like terminal 15 are also bent inwardly by this same operation as illustrated in Fig. 17 to establish electrical connection with the strands of the wire 11 through the insulation 17. The extent to which the raw edge of the sleeve-like terminal is curled into the material of the insulation on the conductor is determined by the shape of the shoulder 11j on the spring collet chuck and the proportions of the interior of the spring collet chuck with respect to the length of the terminal sleeve.

The actuating means 12a and 12b are employed to effect the foregoing collapsing operation. When the actuating means is released the springs 6 and 7 force the knives to retracted positions illustrated in Fig. 3 preparatory for a repeat operation.

As heretofore explained, in lieu of the hand actuated means 12a and 12b, I may provide foot actuating means or motor drive means for effecting a terminal applying operation.

I have shown my invention in one of its preferred embodiments for applying a cylindrical sleeve-like tip or terminal to the end of an electrical conductor. It will be understood that various forms of terminals may be applied to the ends of an electrical conductor in accordance with my invention. That is, a flat terminal having an eyelet or a yoke-shaped end with a sleeve-like portion formed integral therewith may be applied to the end of an electrical conductor in accordance with my invention. Moreover a terminal of square or rectangular section may be applied to the end of the conductor in lieu of the cylindrical sleeve-like terminal illustrated herein. The tool of my invention is also applicable to terminals of deformed or split section construction as distinguished from the solid cylindrical sleeve terminal illustrated herein. I may also vary the number of knives which are employed in the tool and it is to be understood that the illustrations herein are to be regarded in the broad sense and not in the limiting sense.

While I have explained my invention in certain preferred embodiments, I realize that modifications may be made and I desire that it be understood that no limitations upon my invention are intended other than may be imposed by the scope of the appended claims.

What I claim as new and desire to secure by Letters Patent of the United States is as follows:

- 30 1. Mechanism for applying terminals to electrical conductors comprising a shell having a restricted opening in one end thereof, a sleeve movable into and out of said shell; a spring collet chuck member yieldingly supported in the end of said sleeve, a plurality of radially movable knives coacting with said spring collet chuck member, means within said sleeve for radially moving said knives inwardly, said chuck having an internal bore for receiving the end of a terminal encased insulated electrical conductor, said knives operating to pierce the material of the terminal and displace said material inwardly into electrical connection with said electrical conductor through the insulation thereof, and means for applying pressure to the aforesaid means for moving said knives inwardly toward the terminal encased electrical conductor.
- 35 2. A device for applying sleeve-like members to insulated electric wire and establishing electrical connection therewith comprising a socket member having a multiplicity of separable portions normally spaced for permitting the insertion of a terminal sleeve capped insulated wire therebetween, knife members rockably mounted between said separable portions, said knife members having blades thereon for piercing the material of the terminal sleeve and displacing material from said terminal sleeve inwardly for establishing electrical connection with said wire, means for applying pressure to said knife members for moving said knife members inwardly toward said terminal sleeve, and spring means for retracting said knife members.
- 40 3. A device for applying sleeve-like members to insulated electric wire and establishing electrical connection therewith comprising a socket member having a multiplicity of separable portions normally spaced for permitting the insertion of a terminal sleeve capped insulated wire therebetween, knife members rockably mounted between said separable portions, said knife members having blades of isosceles shape for piercing and displacing triangular portions of the material of said terminal sleeve through the insulation

- 60
- 65
- 70
- 75

of the insulated electrical conductor and into electrical connection with said wire, means for applying pressure to said knife members for moving said knife members inwardly toward said terminal sleeve, and coil springs for retracting said knife members for releasing said conductor with the terminal sleeve applied thereon.

4. A device for applying sleeve-like members to insulated electric wire and establishing electrical connection therewith comprising a socket member having a multiplicity of resiliently mounted portions with radial slots therebetween, knife members angularly shiftable through the radial slots of said socket member, means for angularly displacing said knife members through the slots in said socket member for piercing the material of a terminal sleeve inserted into said socket and displacing portions of said material into electrical connection with said electric wire, and means for applying force to the aforesaid means for moving said knife members inwardly toward said terminal sleeve.

5. A device for applying sleeve-like members to insulated electrical conductors and establishing electrical connection therewith comprising a cylindrical socket member, a shell member slidable over said cylindrical socket member, a collet chuck concentrically arranged within said socket member and projectible through said shell member, an internal annular shoulder formed by said collet chuck, a plurality of knives disposed within said collet chuck and having cam-like portions engageable by said socket member as said shell member is shifted with respect to the socket member for piercing the material of a sleeve-like terminal carried by an electrical conductor insertable between said knives in retracted position with the raw edge of the sleeve-like terminal enveloped by the internal shoulder formed by said collet chuck for displacing the material of the sleeve-like terminal into electrical connection with the insulated electrical conductor and curling the raw edge of said sleeve-like terminal into connection with the insulation of said insulated electrical conductor, said knives being retractible from said engaging position when said shell is shifted with respect to said socket member, and means for applying force to said shell member for displacing said collet chuck with respect to said socket member for moving said knives inwardly toward said sleeve-like terminal.

6. A device for applying sleeve-like members to insulated electrical conductors and establishing electrical connection therewith comprising a cylindrical socket member, a shell member slidable over said cylindrical socket member, a pair of coil springs disposed in said socket member, a plunger having a headed end yieldingly supported by one of said coil springs, a collet chuck slidably disposed over said plunger, said collet chuck having longitudinally extending portions with radially disposed slots therebetween, knives rockably mounted in the radially disposed slots, said other

coil spring being disposed between the headed end of said plunger and said collet chuck, said knives being movable radially inwardly for piercing the cylindrical sleeve-like member carried by the electrically insulated conductor inserted through the open end of said collet chuck for establishing connection between the material of said sleeve-like member and the electrical conductor, and means for applying pressure to said knives for moving said knives inwardly toward said sleeve-like member.

7. A device for applying sleeve-like members to insulated electric wire and establishing electrical connection therewith comprising a socket member having a multiplicity of resiliently mounted portions with radial slots therebetween, knife members angularly shiftable between the radial slots of said socket member, an annular shoulder formed interiorly of said socket member, a plunger axially movable through said socket member, said plunger forming a movable support for the sleeve-like capped end of an insulated electric wire insertable through said socket member, means for shifting said plunger axially through said socket member, means for closing said socket member against said conductor whereby said shoulder forms an abutment against which the raw edge of the terminal sleeve is moved for curling said sleeve inwardly against the insulation of the electric wire, and means for angularly moving said knife members through the slots in said socket member for piercing and lancing the material of the terminal sleeve and establishing connection between the material of the terminal sleeve and the electric wire.

8. A device for applying sleeve-like members to insulated electric wire and establishing electrical connection therewith comprising a socket member having a multiplicity of resiliently mounted portions with radial slots therebetween, knife members angularly shiftable between the radial slots of said socket member, a plunger axially movable through said socket member and operative to form a support for the sleeve-like capped end of an insulated electric wire introduced through the socket member, means for compressing the end of said socket member against the insulation of the electric wire introduced therein in a position displaced from the raw edge of the sleeve-like terminal carried thereon, an annular shoulder formed interiorly of said socket member, means for displacing said plunger for moving the sleeve-like terminal thereon to a position in which the raw edge of the sleeve-like terminal is engaged by the said shoulder and rolled inwardly to grip the insulation of the electric wire, and means for moving said knife members radially inward for piercing and lancing the material of said sleeve-like terminal for establishing connection between the sleeve-like terminal and the electric wire through the insulation thereof.

LEON ROSENTHAL.
